Primary Examiner—Donald P. Walsh*Assistant Examiner*—Martha Thompson*Attorney, Agent, or Firm*—Armstrong, Nikaido, Marmelstein, Kubovcik & Murray[57] **CLAIM**

The ornamental design for a ball-point pen, as shown and described.

DESCRIPTION

FIG. 1 is a top, left front perspective view of a ball-point pen showing my new design;

FIG. 2 is a front elevational view;

FIG. 3 is a rear elevational view;

FIG. 4 is a left side elevational view, the right side being a mirror image thereof;

FIG. 5 is a top plan view;

FIG. 6 is a bottom plan view;

FIG. 7 is a right front perspective view in an exploded condition; and,

FIG. 8 is a top plan view of FIG. 7 with the cap member removed for convenience of illustration.

FIG. 1

FIG. 7
